(57) **CLAIM**

The ornamental design for a handle for a two-finger knife, as shown.

DESCRIPTION

FIG. 1 is a side elevational view of the invention on a two-finger knife having an arc-shaped blade;

FIG. 2 is a bottom view of the invention on the two-finger knife of FIG. 1;

FIG. 3 is an opposite side elevational view of the invention

shown on the two-finger knife of FIG. 1; and,

FIG. 4 is a top view of the invention shown on the two-finger

knife of FIG. 1.

The broken line portions of the disclosure are for illustrative

purposes only and form no part of the claimed design.
